UNITED STATES PATENT OFFICE.

AARON S. NICHOLS, OF NEW YORK, N. Y.

LUMBER-STICKING APPARATUS.

1,283,871.

Specification of Letters Patent. Patented Nov. 5, 1918.

Application filed December 4, 1917. Serial No. 205,430.

To all whom it may concern:

Be it known that I, AARON S. NICHOLS, a citizen of the United States, and a resident of the city, county, and State of New York, have invented a new and useful Improvement 5 in Lumber-Sticking Apparatus, of which the following is a full, clear, and exact description.

My invention relates to improvements in 10 apparatus for sticking lumber preparatory to drying. In preparing lumber, lumber stock, or similar things for drying and for proper preservation, the customary way is to lay pickets between the several layers of 15 stock so as to provide for a free circulation of air. This entails a good deal of work, is inconvenient, and results in the loss of a good many pickets, or at least their displacement and temporary loss, so that the expense in- 20 volved is considerable. The object of my invention is to produce an apparatus by which the separating elements or slats which take the place of the ordinary single pickets are always at hand, and can by the slight- 25 est labor be dropped to place between the several layers of stock, and can when the stock is to be unpiled, be displaced by simply moving them back, when they will swing out of the way and not interfere with the 30 labor of handling the stock. In this way they can be used over and over, are always ready for use, are never displaced, and the arrangement is such that they are not likely to be broken. My invention further con- 35 templates the arrangement of these separating elements so that they will always be in alignment one above the other, which is necessary in order that the stock may be held properly, and the arrangement is also such 40 that the freest possible circulation of air between the stock layers is provided for. In carrying out my invention in one of its preferred forms, I apply the apparatus to a truck so that the stock can be quickly and 45 suitably piled upon the truck and then moved into a dry kiln, but the principle of the apparatus is the same when it is applied in a stationary way for the purpose stated. All of which will be more clearly understood 50 from the description which follows.

Reference is to be had to the accompanying drawing, forming a part of this specifi-

cation, in which similar reference characters indicate corresponding parts in all the views.

Figure 1 is a broken side elevation of the 55 apparatus embodying my invention.

Fig. 2 is a sectional plan on the line 2—2 of Fig. 1.

Fig. 3 is a broken perspective view of a 60 part of the apparatus, and

Fig. 4 is a detail of a part of a guide post.

The platform 10 I have shown as a part 65 of a portable truck, and it is provided with the customary or any preferred corner posts 11 and with removable side posts 12 which are left off entirely on one side when the stock is piled upon the truck so that the two posts on the other side will serve as abutments to assist in piling the stock evenly. 70 Obviously if the truck is used any suitable form of truck can be employed. At the ends of the truck are guide-ways which carry the elements for separating the stock, and a preferred form of guide-way is shown in 75 the drawings in which vertical side posts 13 are attached to the posts 11 and extended beyond the truck end, having inturned flanges 14 to limit the outward movement of the cross-heads 18. Short parallel partitions 15 80 are arranged one above the other and inclined upwardly from the back of the guide-way as shown clearly in the drawings, forming ways 16 between them. The inner ends of the partitions 15 are spaced apart from 85 the posts 11 so as to leave a vertical way 17 in which the cross-heads 18 of the slats 19 can move.

Obviously the guide-ways 16 arranged at 90 an incline as shown can be produced in any convenient way without affecting my invention, so long as they are inclined and adapted to receive the cross-heads 18. I have shown a convenient way in which the inner sides of the guide posts 13 are provided with 95 parallel inclined grooves 15 in which the partitions 15 are secured. Thus the cross-heads 18 and slats 19 are tilted in the ways 16, the flanges 14 prevent the cross-heads from being thrown back too far, and the 100 posts 11 prevent the cross-heads and slats from being pulled forward too far. It will be noticed by reference to the drawing that each cross-head lies above the top of one par-

tition 15, and below the top of the next partition, so that assuming that the cross-head is drawn into the position shown in the lower part of Fig. 1, and it is desired to move the cross-head and the connected slats 19 out of the way, the operator simply pushes the slats back and the cross-head striking the under side of one of the partitions 15, tips up and slides down in the way 16, thus raising the slats 19 as shown in the upper part of Fig. 1. It will be seen, therefore, that the ways have a cam action on the slats so that the operator does not have to lift them and place the cross-head in the way 16, but simply throws them back. If on the other hand he wishes to lower them, he simply pulls the slats and the cross-head 18 out of the way 16, and the slats fall to a horizontal position, and the cross-head lies in the way 17 in which it can move freely and vertically.

This way 17 therefore provides for the vertical movement of the cross-heads, and it will be noticed that varying thicknesses of stock can be used, and the cross-heads simply pushed into the next adjacent way 16.

To provide for a still better adjustment of the slat elements with relation to the ways 16, and for variations of thickness in the stock, I prefer to make the guide posts 13 vertically adjustable. A convenient way to do this is to provide them with slots 18^a (see Fig. 3) and with nuts and bolts 13^b connecting through the slot with the post 11. Thus by loosening the nuts the guide posts 13 can be raised or lowered and then held in place by tightening the nuts.

I provide foundation slats 20 on the floor of the truck 10 or the bed of the piling apparatus, and on this the stock 21 is laid, then the lower slats 19 are pulled out as described and dropped upon the stock, then more stock is piled on these, the next slats adjusted as before, and so on. Obviously the foundation slats 20 are not necessary, and if desired a set of slats 19 can be laid directly on the floor of the truck or the bed of the piling apparatus, and when the stock is piled it will be seen that the slats 19 separate the sheets as usual, and that the posts 11 prevent the stock from coming out even with the cross-heads 18, thus providing air space between the cross-heads and the edges of the stock so that the air can pass freely between the several layers.

It will be seen that the guide posts 13 prevent the lateral displacement of the cross-heads, and that the several slats 19 will lie in vertical alinement with the stock 21 between them. This is important as the bearing always comes in the same place and the stock is prevented from being warped or twisted.

In the drawings I have shown a truck

provided with two sets of sticking apparatus, one at each end, but obviously the principle is the same whether applied to one or both ends, and it will be seen that the sticking apparatus can be used as well on a stationary bed as on a portable truck, and it will also be noticed that the arrangement at the ends and sides is such as to provide for the freest circulation of air between the stock layers.

As before stated, the posts 12 are left on the truck at the back side so that the operator can insert the stock freely from the front side. When not in use the slats 19 are tipped up as shown at the upper part of Fig. 1, and they are pulled out and dropped to place as the piling of the stock proceeds.

Attention is called to the fact that the apparatus is so simple as to be inexpensive, and that it can be made strong, and when once in place can not be displaced and is therefore always ready for use.

While the preferred means of tilting the slats 19 by throwing them back has been described and illustrated, the invention is not limited to the means shown as it is thought that sticking slats for stock have never been arranged before in this manner so as to be automatically tilted out of the way by throwing them back. It will also be noticed that the arrangement is compact, the tilted slats are out of the way of the workmen and within the body of the truck or piling apparatus, and in position to be readily pulled forward and dropped to place as needed.

I claim:

1. An apparatus of the kind described comprising a series of slats loosely supported one above the other, and adapted to lie in either a horizontal or inclined position, and means near one end of the slats for tipping them up into an inclined position by the endwise movement of the slat.

2. An apparatus of the kind described comprising a series of superposed slat elements each comprising slats spaced apart and connected together, said elements being adapted to lie in parallel position one above the other, and means for tipping the slats up into an inclined position by moving them endwise.

3. An apparatus of the kind described comprising a series of slat elements adapted to lie one above the other, each comprising slats spaced apart and connected by a cross-head, and a series of inclined ways opposite the cross-heads, said ways being adapted to receive said cross-heads.

4. An apparatus of the kind described comprising a plurality of slat elements arranged one above the other, each comprising slats and a connecting cross-head, a vertical way for the movement of the cross-heads

therein, and inclined ways opposite the vertical way, the inclined ways being adapted also to receive the cross-heads.

5. An apparatus of the kind described comprising a vertical way, a series of inclined partitions behind the vertical way and opening therefrom, cross-heads movable in the vertical way and adapted to enter the inclined ways, and slats projecting from the cross-heads.

6. An apparatus of the kind described comprising a series of rectangularly arranged guide posts spaced apart and the opposite posts provided with vertical ways and inclined ways opening from the vertical ways, and slat elements arranged one above the other each having cross-heads movable in the vertical ways and adapted to enter the inclined ways.

20 7. An apparatus of the kind described comprising vertical guide posts spaced apart and provided with a vertical way and with a plurality of inclined ways opening from the vertical way, and a plurality of slat elements having cross-heads adapted to move vertically in the vertical way and fit in the inclined ways, whereby the slat elements are tipped up when the cross-heads are in said inclined ways.

30 8. An apparatus of the kind described comprising a portable bed, guide posts spaced apart on the bed and provided with a vertical way and with inclined ways opening from the vertical way, and a plurality of slat elements having cross-heads movable in the vertical way and adapted to fit in the inclined ways.

9. An apparatus of the kind described comprising a vertical way, a series of superposed slat elements having cross-heads movable in the way, and means for tilting the slats by moving them endwise.

10. An apparatus of the kind described comprising vertical posts spaced apart, superposed slat elements projecting between

the posts and having cross-heads movable behind the posts, a vertical way behind the aforesaid posts, and means for tilting the slat elements by moving them endwise.

11. An apparatus of the kind described 50 comprising a support, vertically adjustable posts on the support, spaced apart and provided with inclined ways one above the other, and slat elements arranged to move up and down between the posts and to fit in 55 the inclined ways each slat element comprising a cross-head, and finger-like slats spaced apart and projecting from the cross-head.

12. An apparatus of the kind described comprising a series of slat elements adapted 60 to lie one above the other, each comprising slats spaced apart and connected by a cross-head, and a series of inclined ways opposite the cross-head said ways being adapted to receive said cross-heads and being vertically 65 adjustable.

13. In an apparatus for sticking lumber characterized by a series of slat elements freely movable one above the other, such slat elements each comprising a cross head, and 70 slats spaced apart and projecting from the cross head.

14. In an apparatus for sticking lumber characterized by a series of independent slat elements freely movable one above the 75 other, such slat elements each comprising a cross head, and slats or fingers spaced apart and projecting from the cross head, the said slats or fingers being unconnected at their free ends.

15. In an apparatus of the kind described, the slat element comprising a plurality of fingers or slats spaced apart in parallel relation and connected together at one end only.
